UNITED STATES PATENT OFFICE

167,474

SHINGLE ROOF OR THE LIKE

Roger S. Nettles, Jackson, Miss.

Application May 21, 1951, Serial No. 15,269

Term of patent 14 years

(Cl. D68—1)

To all whom it may concern:

Be it known that I, Roger S. Nettles, a citizen of the United States, residing at Jackson, in the county of Hinds and State of Mississippi, have invented a new, original, and ornamental Design for a Shingle Roof or the like, of which the following is a specification, reference being had to the accompanying drawing, forming part thereof.

Figure 1 is a detail plan view of the shingle element used to form the roof; and

Figure 2 is a plan view of a section of shingle roof, showing my new design.

I claim:

The ornamental design for a shingle roof or the like, as shown.

ROGER S. NETTLES.
